UNITED STATES PATENT OFFICE.

WILLIAM M. SCOTT, OF PHILADELPHIA, PENNSYLVANIA.

ELECTROPNEUMATIC CONTROL APPARATUS.

1,096,061.

Specification of Letters Patent.

Patented May 12, 1914.

Application filed October 25, 1910. Serial No. 588,938.

To all whom it may concern:

Be it known that I, WILLIAM M. SCOTT, a citizen of the United States, residing at Philadelphia, in the county of Philadelphia 5 and State of Pennsylvania, have invented a new and useful Electropneumatic Control Apparatus, of which the following is a specification.

My invention relates to electro-pneumatic control apparatus for controlling, from a more or less remote point, electric circuits or branches or sections adapted to carry heavy currents for lighting, power, or other purposes.

15 My invention resides in apparatus, such as above referred to, and comprises an electric switch or circuit breaker, which may be of the "non-closable" type, and pneumatic apparatus for actuating and controlling the same, together with electrically controlled means for controlling the pneumatic apparatus.

20 My invention resides in apparatus such as above referred to, and in one mode of its use or application may be mounted in stations along a portion of an electric railway and form the connections between successive sections of the third rail or other contact conductor, and may be used to automatically disconnect such sections of the rail as may become grounded, and may reconnect them when normal conditions have been reestablished.

25 My invention resides in other features hereinafter described and claimed.

For an illustration of one of the forms my apparatus may take, and for an illustration of one of its modes of application or use, reference is to be had to the accompanying drawings, in which:

30 Figure 1 is a side elevational view, some parts in section, of a circuit breaker with the accompanying pneumatic operating means. Fig. 2 is a side elevational view of a control switch. Fig. 3 is a front elevational view of the same. Fig. 4 is a sectional view through the main pneumatic valve. Fig. 5 is a front elevational view of a circuit breaker and its pneumatic operating means, 35 together with the controlling means, the base of the apparatus being omitted. Fig. 6 is a vertical sectional view through the magnetically controlled pneumatic valve. Fig. 7 is a diagrammatic view illustrating one mode of application or use of my apparatus. Fig. 8 is a diagrammatic view illus-

trating a mode of use of my apparatus with duplicated control circuits. Fig. 9 is a fragmentary view illustrating the connection between the operating lever and the piston rod. 60

Upon the base 1, Fig. 1, of suitable insulating material, such as slate or marble, are disposed the main terminal blocks 2 and 3 of a switch or circuit breaker, studs 4 and 5 extending through the base 1 and communicating respectively with the main contacts 2 and 3. Adapted to bridge and connect the main terminal blocks 2 and 3 is provided the movable contact member 6, here shown laminated; the bridging member 6 is secured upon the arm 7 pivoted at 8 to the housing 9. Secured upon and in electrical communication with the upper main terminal block 2 are the intermediate metallic shunt contact 10 and the carbon shunt contact 11, the latter pivoted at 12 upon the bracket 13. Coöperating with these shunt contacts are the movable metallic shunt contact 14 and the movable carbon shunt contact 15 engaging respectively with the contacts 10 and 11. The movable shunt contacts 14 and 15 are in electrical communication with each other and by the flexible conductor 16 in permanent electrical communication with the lower main contact 3. 70

80 Pivoted on the arm 7 at 17 is the roller 18 adapted to be engaged by the cam surface 19 upon the operating lever 20 pivoted to the housing 9 at 21. Springs 20^a are attached to lever 20 and to the housing 9, 85 for rotating the lever 20 in a counter-clockwise direction (Fig. 1) when the breaker is tripped. Pivoted at 21 to the housing 9, but independently of the lever 20 is the actuator 22 having the transversely extending web 90 23 against which is adapted to abut the lug 24 upon the dog 25 pivoted to the actuator 22 at 26. The dog 25 also has a lug 27 which is adapted to engage the web 23 to limit the pivotal movement of the dog 25 95 100 in clockwise direction upon its pivot 26, as viewed in Fig. 1. On the lever 20 is pivoted the roller 28, Fig. 5, adapted to be engaged by the hook latch 29 having limited movement upon the pivot 30, on the housing 9, 105 a spring, not shown, urging the latch 29 upwardly. Independently pivoted at 30 is a member 31 also having limited movement upon said pivot. A member 32 is also independently pivoted at 30 and has a tail 33, 110 and carries two adjustable screws 34, one adapted to engage upon the top of the mem-

ber 31 and the other upon the top of the latch 29. Pivoted at 35 on the lever 20 is the dog actuator 36 having limited movement upon the pivot 35, the limiting of the movement being secured by the lugs 37 and 38 adapted to engage the second roller 28^a carried on member 20 beside roller 28. The dog actuator 35 has a lug 39 adapted to engage the nose 40 of the dog 25 to move the same from engagement with the roller 28^a. A spring 32^a tends to hold the member 32 raised. The tail 33 of the member 32 extends into the path of travel of the member 41 pivoted to the base at 42 and carrying the armature 43 adapted to be attracted toward the base 1 when the current through tripping winding 3^a, shown diagrammatically in Fig. 7, of the switch or circuit breaker attains a predetermined value. The position of the armature 43 with respect to the poles which attract it, may be adjusted by the transverse adjustment of the handle 44.

The circuit breaker mechanism thus far described is similar to that described in my co-pending application Serial No. 563366, filed May 25, 1910.

Secured to the base 1 is the jacket or housing 45 of an electro-magnet whose winding 46 and whose armature is 47. Attached to armature 47 is a vertically extending rod 48 which is limited in its downward movement by the collar 49 which at its upper end carries a nut 50 adapted to strike the underside of the tail 33.

Secured upon the base 1 beneath the circuit breaker is the pneumatic cylinder 51 within which is movable the piston 52, the piston rod 53 extending through the cylinder head 54 and carrying at its top a transversely extending yoke or bar 55, to which is pivoted at 56 the downwardly extending links 57 pivoted at their lower ends to the double levers 58 pivoted at 59 in the bracket 60. Tension springs 55^a are secured to the bar or yoke 55 to hold the links 57 in their downward position, shown in Fig. 1. In the cylinder head 54 is a valve 61 held against its seat by the upwardly acting spring 62. When the piston 52 descends in the cylinder 51, the valve 61 opens against the opposition of spring 62 and allows ready ingress of air to prevent a partial vacuum above the piston 52.

Back of the base 1, Fig. 1, is the main pneumatic valve 63 shown in vertical section in Fig. 4. With the top of this valve communicates the pipe 64, communicating with the supply pipe 65 which leads to a compressed-air tank or reservoir, not shown. A spring 66 holds the valve 67 down upon its seat 68. A downwardly extending rod 69 is secured upon the valve 67, and is surrounded by spring 70 which opposes the upward movement of the stem 71 on the

plunger 72 disposed in the chamber 73 with which communicates the pipe 74 leading to the magnetically controlled pilot valve shown in Fig. 6. With the side of the valve 63 communicates a pipe 75, which communicates with the lower end of the cylinder 51.

The pipe 74 of valve 63 communicates with the port 77 of the magnetically controlled valve 76, see Figs. 5 and 6. The valve 78 is seated in the member 79 and held against its seat by the spring 80 resting at its lower end upon the perforated diaphragm 81 in the member 82 having the central aperture 83 communicating with the pipe 84 communicating with the air supply pipe 65, Fig. 1. The valve 78 closes communication between the supply pipe 84 and the port 77 and is supported upon a rod or needle 85 which may be forced downwardly by the rod 86 which is attached at its upper end to the armature 87 of an electro-magnet whose winding is 88, inclosed by casing 88^a, a flat spring 89 normally holding the rod 86 elevated when the winding 88 is deenergized. When the electro-magnet is energized the rod 86 is depressed, lifting the valve 78 from its seat in opposition to the spring 80, whereupon air passes from the supply pipe 84 to the port 77 and thence through pipe 74 to the valve 63. With the rod 86 thus depressed the ports 90 are closed by rod 86 closing passages 85^a; when the magnet is deenergized the spring 80 returns the valve 78 against its seat and the spring 89 lifts the armature 87 and rod 86 and simultaneously the ports 90 are opened, allowing exhaust from port 77 and pipe 74 to the external atmosphere.

Upon a crank 91, attached to and movable with the operating lever 20, there is pivoted at 92 a downwardly extending rod 93 pivoted at its lower end at 94 to the actuating member 95 of a snap switch mounted in front of the cylinder 51, Figs. 1 and 5. This snap switch is shown in larger scale in Figs. 2 and 3, and is shown to be insulated from its support by the insulating material 96. The switch comprises two pairs of stationary contacts, one pair 97 and 98 and the other 99 and 100. The switch blades 101 and 102 are electrically connected to each other and adapted to engage respectively the contacts 97 and 98. The switch blades 103 and 104 are electrically connected together and are movable with but insulated from the switch blades 101 and 102, and are adapted to engage respectively the switch contacts 99 and 100. When the switch blades 101 and 102 are in engagement with contacts 97 and 98, the parts are latched in such position, and in such case the switch blades 103 and 104 are out of engagement with switch contacts 99 and 100. When the switch or circuit breaker is tripped, the rod 93 moves upwardly and carries the switch blades 101 and 102

102 into engagement with contacts 97 and 98 and removes switch blades 103 and 104 from contacts 99 and 100. When the circuit breaker or main switch is closed, the rod 93 moves downwardly and winds up the snap switch spring 105 and thereafter removes the detent to allow the blades 101 and 102 to snap away from contacts 97 and 98, and simultaneously switch blades 103 and 104 engage contacts 99 and 100.

Pivoted at its lower end at 106 is the rod 107 pivoted at its upper end to the actuator 22 of the switch or circuit breaker.

Upon the base 1, see Fig. 5, there is mounted also an electro-magnet or relay having armature 108 and winding 109 (Fig. 7) said winding being inclosed in a casing 110. The armature 108 carries rod 111 upon which is supported, though insulated from it, the bridging member 112 resting upon the spring 113 which, in turn, rests upon the nut 114 upon the rod 111. When the electro-magnet is energized, the armature 108 is held in raised position bringing the contact member 112 into engagement with and connecting the contacts 115 and 116.

Referring to Fig. 7, B is an automatic circuit breaker, located, for example, at a power station, current being passed through the breaker to the various sections each controlled by a section breaker S, such as shown in Fig. 1. The breaker B is shown simplified, and as comprising main terminal blocks *a* and *b*, bridged by the main movable contact *c*, an overload coil *e* serving for tripping purposes as well understood in the art. When the circuit breaker B is closed, in the position shown in Fig. 7, it holds the bridging contact *f* out of engagement with the contacts *g* and *h*, thus interrupting the circuit extending from the storage battery or other source of energy *i* through the fuse *j*, conductor *k*, switch *m*, incandescent lamp *n*, conductor *o*, contact *g*, member *f*, contact *h*, conductor *p*, tripping coil 46, conductor *q*, fuse *r* to battery *i*. When, however, the station circuit breaker B is tripped and opens, the contact *f* is forced into engagement with contacts *g* and *h*, by a spring, not shown, closing the circuit just traced and energizing the electro-magnet 46 which then attracts its armature 47, and through rod 48 and nut 50 lifts the tail 33, Fig. 1, depressing the member 32 which, thereupon, depresses latch 29 to free the movable parts of the section breaker S, such section breaker being accordingly tripped and opened. When the station breaker B is again closed, the contact *f* is separated from contacts *g* and *h*, again opening the circuit of the tripping coil 46. When the section breaker S opens, the contacts 97 and 98 are bridged through switch blades 101 and 102, short circuiting the trip coil 46; and, simultaneously, switch blades 103 and 104 separate from contacts

99 and 100, removing the short circuit from the magnet winding 88.

With conditions restored in the station, if it be desired to close the distant breaker S, the switch *m* is thrown over to the right, Fig. 7, to engage contact *s*, whereupon current will flow from battery *i*, through fuse *j*, conductor *k*, switch *m*, lamp *n*, conductor *t*, contact 115, bridging member 112, contact 116, conductor *u*, winding 88, conductor *v*, to conductor *q*, through fuse *r* to battery *i*. The electro-magnet 88 is, therefore, energized and removes valve 78 from its seat, allowing air from the compressed air supply to pass in through pipe 84 to port 77, thence through pipe 74 to valve 63. The air pressure lifts the plunger 72 which then rises to the upper end of its chamber 73 closing off the passage 71^a which communicates through port 71^b to the external atmosphere, and compresses spring 70 and lifts valve stem 69 lifting the valve 67 from its seat 68 in opposition to spring 66, allowing air from the compressed air supply to flow from pipe 64 past the valve 67 and into the pipe 75 through passage 75^a to cylinder 51 below piston 52 which rests on stop 52^a. The circuit breaker S in opening, has rotated the lever 20 in counter-clockwise direction, as viewed in Fig. 1, until the roller 28^a has come into engagement with the nose 40 of the dog 25. And the actuator 22 carrying the dog 25 has remained in elevated position, as shown in Fig. 1, due to the action of the springs 55^a. The actuator 22 and the lever 20 are accordingly mechanically connected for any downward movement of the rod 107. The admission of the air to the underside of the piston 52, therefore, raises said piston carrying the links 57 upwardly and causing them to rotate levers 58 in a clockwise direction about their pivot 59, pulling downwardly on the rod 107. This action returns the circuit breaker S to normal position, the latch 29 engaging the roller 28 when this position is reached. With the closure of the circuit breaker S the rod 93 has been depressed, causing switch levers 101 and 102 to separate from contacts 97 and 98 and to cause the bridging of contacts 99 and 100 by the switch levers 103 and 104, short circuiting the winding 88 of the magnet which controls the pilot air valve. This magnet is deenergized by this short circuiting, and the spring 89 accordingly raises rod 86 and allows spring 80 to close the valve 78 and to allow an exhaust of air from the port 77 and the pipe 74 which connects with it. Thereupon, the spring 70 returns the plunger 72 to its lowermost position, as viewed in Fig. 4, and the communication afforded by port 71^a and port 71^b allows communication to the outer atmosphere above the plunger 72 and exhaust from cylinder 51. The valve 130

68 accordingly returns to its seat and shuts off the air supply from the pipe 75 to the lower end of the cylinder 51. The springs 55^a contract and pull downwardly upon the 5 links 57 which engage the levers 58 and lift the rod 107 to return the actuator 22 to the position shown in Fig. 1, and to insure the prompt return of the piston 52 to the bottom of the cylinder 51, the valve 61 opens 10 and allows ingress of air to prevent vacuum above the piston 52.

The operator at the station where breaker B is located may return the switch *m* to the left hand position, as viewed in Fig. 7, 15 and the operations herein described may then be repeated.

If it should be attempted to close the section breaker S during the time that winding 46 of the tripping magnet is energized, 20 or during the occurrence of a predetermined or other electrical condition upon the circuit including tripping coil 3^a, the tail 33 will be held elevated and the latch 29 depressed, as well as the dog actuator 36, this 25 action preventing the closure of the circuit breaker during any of these conditions; *i. e.*, the circuit breaker is shown as a "non-closable" breaker.

The circuit of the pilot valve magnet 88 30 is controlled by the relay or electro-magnet 109, one terminal of the winding 109 being connected to the section of third rail or other contact conductor *w*, while the other terminal is connected to earth or other re- 35 turn *x*. While substantial voltage remains upon the line section, the electro-magnet 109 remains energized and keeps the circuit closed at contacts 115, 112 and 116. But should the voltage upon the line fall below 40 a predetermined limit, the armature 108 will fall and bridging member 112 will separate from contacts 115 and 116, thus preventing the energization of the magnet 88 during 45 the continuance of this condition. From this it follows that the section breaker S cannot be restored to circuit closing position during this condition upon the section of the line.

In Fig. 8 is shown diagrammatically an 50 arrangement of duplicate control circuits for the section breaker S. Two trip coils 46 and 46^a are provided as well as two pilot valve magnets 88 and 88^a; the snap switch having duplicated contacts, the upper contacts controlling the pilot valve magnets, 55 while the lower contacts control the tripping coils.

If the operator wishes to trip the breaker S, he pulls outwardly on the handle 117 in 60 opposition to the spring 118, bringing the contact 119 into engagement with contacts 120 and 121, short circuiting the indicating lamp 122 and allowing current to flow from battery *i*, through fuse *r*, contacts 120, 119, 65 121, conductor 123, thence from contact 98

to contact 97, through the blades 102 and 101, thence by conductor 124 through the tripping coil 46, conductor 125; through fuse *j* to battery *i*. The coil 46 is accordingly energized and trips the circuit breaker. 70 And, similarly, if the left hand control should be out of order the right hand control may be employed to similarly energize the duplicate tripping magnet 46^a, by the operator pulling outwardly upon the handle 75 117^a, the magnet 46^a operating upon the same tripping member as magnet 46.

The movable switch blades of the duplicated snap switch all move together, and, accordingly, when the breaker S is tripped 80 by either magnet 46 or magnet 46^a, contacts 97 and 98 are disconnected from each other, while contacts 99 and 100 are bridged by 103 and 104 and 99^a and 100^a are bridged by 103^a and 104^a. Then the operator may close the 85 breaker S by either the left hand or right hand control. Pulling outwardly upon the handle 126 in opposition to spring 127, causes the contact 128 to bridge the contacts 129 and 130 to short circuit the indicating 90 lamp 131 and allow current to pass from the battery *i*, through fuse *r*, contacts 129, 128, 130, conductor 132, contact 100, contacts 104, 103, 99, conductor 133, thence through the winding 88 of the pilot valve magnet and resistance 134 in parallel, thence through fuse *j* to battery *i*. This energizes the pilot valve which, in turn, controls the main valve 63, which allows compressed air to pass into the cylinder 51 to move the piston 52 to close the 100 breaker, as hereinbefore described. Or, if the left hand control circuit is out of order, the right hand circuit may be employed, whereupon pulling outwardly upon the handle 126^a 105 will cause the pilot valve magnet 88^a to be energized to control the same pilot valve.

The resistances 134, 134^a are employed when the magnets 88 and 88^a are to be used with a control circuit of a potential so great 110 that if the resistances were not used the windings 88 and 88^a would overheat.

It will be noted that in the arrangement of Fig. 8, the magnets 46 and 46^a and 88 and 88^a are not short circuited by the controlling 115 snap switch, but that the contacts of this switch are in series with the magnets. This may also be the arrangement employed in connection with Fig. 7.

In connection with Fig. 8, a relay, similar to 109, of Fig. 7, may be employed, two pairs of contacts being then provided, one pair located in series in the conductor 132 or conductor 133, while the other pair is located in series in the conductor 132^a, or conductor 125 133^a, so that the pilot valve magnets 88 and 88^a cannot be energized if the voltage on the line has decreased below a certain limit.

When the handles 117, 117^a, 126, 126^a are 130 in the position shown in Fig. 8, the lamps

122, 122^a will indicate by their glowing, that the apparatus is in condition to be tripped; i. e., that the breaker S is closed. After it is tripped, the lamps 122 and 122^a will not glow, but the lamps 131 and 131^a will glow, indicating that the circuit through magnets 88 and 88^a is complete and that the apparatus is in condition to close the breaker S. If either of the control circuits is out of order, it will be indicated by the fact that one or another of the incandescent lamps does not glow.

What I claim is:

1. The combination with the movable contact of a switch or circuit breaker, of an operating member therefor, an actuator for said operating member, tripping mechanism, a pneumatic device acting in one direction to actuate said actuator, and means for returning said actuator to normal position, and means preventing operation of said pneumatic device until after said switch or circuit breaker has been tripped.

2. The combination with a movable contact of a switch or circuit breaker, of an operating member therefor, an actuator adapted to engage and actuate said operating member in one direction, a spring for returning said actuator to normal position, and means moving in unison with said operating member controlling actuation of said actuator.

3. The combination with a movable contact of a switch or circuit breaker, of an operating member therefor, tripping mechanism, an actuator adapted to engage and actuate said operating member in one direction, a spring for returning said actuator to normal position, a pneumatic device for actuating said actuator in one direction to actuate said operating member, and means preventing operation of said pneumatic device until after said switch or circuit breaker has been tripped.

4. The combination with a movable contact of a switch or circuit breaker, of an operating member therefor, tripping mechanism, an actuator adapted to engage and actuate said operating member in one direction, a spring for returning said actuator to normal position, a pneumatic device for actuating said actuator in one direction to actuate said operating member in opposition to said spring, and means preventing operation of said pneumatic device until after said switch or circuit breaker has been tripped.

5. The combination with the movable contact of a switch or circuit breaker, of an operating member therefor, an actuator for said operating member, a pneumatic device acting in one direction to actuate said actuator, means for returning said actuator to normal position, a valve controlling said pneumatic device, and means responsive to

movement of said operating member controlling said valve.

6. The combination with the movable contact of a switch or circuit breaker, of an operating member therefor, an actuator for 70 said operating member, a pneumatic device acting in one direction to actuate said actuator, means for returning said actuator to normal position, a main valve controlling said pneumatic device, a pilot valve controlling said main valve, and means responsive to movement of said operating member controlling said pilot valve.

7. The combination with the movable contact of a switch or circuit breaker, of an operating member therefor, an actuator for 80 said operating member, a pneumatic device acting in one direction to actuate said actuator, means for returning said actuator to normal position, a main valve controlling 85 said pneumatic device, a pilot valve controlling said main valve, electro-responsive means controlling said pilot valve, and a switch movable in definite relation with respect to said movable contact controlling 90 said electro-responsive means.

8. The combination with a movable contact of a switch or circuit breaker, of an operating member therefor, an actuator adapted to engage and actuate said operating 95 member in one direction, a spring for returning said actuator to normal position, a pneumatic device for actuating said actuator in one direction to actuate said operating member, a valve controlling said pneumatic 100 device, and means movable in definite relation with respect to said operating member controlling said valve.

9. The combination with a movable contact of a switch or circuit breaker, of an operating member therefor, tripping mechanism, an actuator adapted to engage and actuate said operating member in one direction, a spring for returning said actuator to normal position, a pneumatic device for actuating said actuator in one direction to actuate said operating member, a valve controlling said pneumatic device, and means actuated with said operating member controlling said tripping mechanism and said 110 pneumatic device.

10. The combination with the movable member of a switch or circuit breaker, of an operating member therefor, an independently movable actuator, electro-responsive 120 means for tripping said switch or circuit breaker, a control switch controlling said electro-responsive means, a motive device for actuating said actuator in one direction only, a switch controlling said motive device, and 125 a connection between said operating member and said control switches for actuating said control switches.

11. The combination with the movable member of a switch or circuit breaker, of an 130

operating member therefor, an independently movable actuator, a tripping magnet for said switch or circuit breaker, a control switch controlling said tripping magnet, a motive device for actuating said actuator in one direction only, a switch controlling said motive device, and means for actuating said control switches independently of said actuator and in unison with said operating member.

12. The combination with the movable member of a switch or circuit breaker, of an operating member therefor, an independently movable actuator, a pneumatic device for actuating said actuator, a valve controlling said pneumatic device, electro-responsive means controlling said valve, a control switch controlling said electro-responsive means, and a connection from said operating member to said control switch for actuating the same.

13. The combination with the movable member of a switch or circuit breaker, of an operating member therefor, an independently movable actuator, a pneumatic device for actuating said actuator, electro-pneumatic means controlling said pneumatic device, electro-responsive means controlling said electro-pneumatic means, a control switch controlling said electro-responsive means, and a connection from said operating member to said control switch for actuating the same.

14. The combination with the movable member of a switch or circuit breaker, of an operating member therefor, an independently movable actuator, a pneumatic device for actuating said actuator, electro-responsive means controlling said pneumatic device, electro-responsive means for tripping said switch or circuit breaker, a control switch for each of said electro-responsive means, and means for actuating said control switches in unison with said operating member.

15. The combination with the movable member of a switch or circuit breaker, of an operating member therefor, an independently movable actuator, a pneumatic device for actuating said actuator, electro-responsive means controlling said pneumatic device, electro-responsive means for tripping said switch or circuit breaker, a control switch for each of said electro-responsive means, and a connection between said operating member and said control switches for operating said control switches.

16. The combination with the movable member of a switch or circuit breaker, of an operating member therefor, an independently movable actuator, a pneumatic device for actuating said actuator, electro-responsive means controlling said pneumatic device, electro-responsive means for tripping said switch or circuit breaker, a control

switch for each of said electro-responsive means, and means operating in unison with said operating member for opening one of said control switches and closing the other.

17. The combination with the movable member of a switch or circuit breaker, of an operating member therefor, an independently movable actuator, a pneumatic device for actuating said actuator, electro-responsive means controlling said pneumatic device, electro-responsive means for tripping said switch or circuit breaker, a control switch for each of said electro-responsive means, and a connection from said operating member to said control switches for opening one of said control switches and closing the other.

18. The combination with the movable contact of a switch or circuit breaker, of an operating member therefor, an independently movable actuator, a motive device for actuating said actuator in one direction only, a switch controlling said motive device, and means for actuating said switch independently of said actuator and in unison with said operating member.

19. The combination with the movable contact of a switch or circuit breaker, of an operating member therefor, an independently movable actuator, a motive device for actuating said actuator in one direction only, means for returning said actuator to normal position, a switch controlling said motive device, and a connection from said operating member to said control switch for actuating the same independently of said actuator.

20. The combination with the movable member of a switch or circuit breaker, of an operating member therefor, an independently movable actuator, a motive device for actuating said actuator in one direction only, electro-responsive means for tripping said switch or circuit breaker, control switches for controlling said motive device and said electro-responsive means, and means for actuating said control switches independently of said actuator and in unison with said operating member.

21. The combination with the movable member of a switch or circuit breaker, of an operating member therefor, an independently movable actuator, a motive device for actuating said actuator in one direction only, means for returning said actuator to normal position, electro-responsive means for tripping said switch or circuit breaker, control switches for controlling said motive device and said electro-responsive means, and a connection from said operating member to said control switches for actuating the same independently of said actuator.

22. The combination with the movable member of a switch or circuit breaker, of an operating member therefor, an independently movable actuator, a motive device for

actuating said actuator in one direction only, means for returning said actuator to normal position, electro-responsive means for tripping said switch or circuit breaker, control switches for controlling said motive device and said electro-responsive means, and means operating independently of said actuator and in unison with said operating member for opening one of said control 10 switches and closing the other.

23. The combination with the movable contact of a switch or circuit breaker, of an operating member therefor, an independently movable actuator, a motive device for actuating said actuator in one direction only, and a control switch controlling said motive device, said control switch controlled in its movement in one direction by said actuator through said operating member, and in opposite direction by said operating member only.

24. The combination with the movable contact member of a switch or circuit breaker, of an operating member therefor, an independently movable actuator, a motive device for actuating said actuator in one direction only, a trip coil for tripping said switch or circuit breaker, and a control switch controlling said trip coil, said control switch controlled in its movement in one direction by said actuator through said operating member, and in opposite direction by said operating member only.

25. The combination with an electric switch having a movable contact member, an operating member therefor, an actuator independent of said operating member adapted to move said operating member in one direction only, means for restraining said contact member in normal position independently of said actuator, a motive device for actuating said actuator in one direction only, a trip coil, and a switch controlling the circuit of said trip coil operated in one direction with said operating member by said actuator, and in opposite direction independently of said actuator.

26. The combination with an electric switch having a movable contact member, an operating member therefor, an actuator independent of said operating member adapted to move said operating member in one direction only, means for restraining said contact member in normal position independently of said actuator, a motive device for actuating said actuator in one direction only, a trip coil, and a switch controlling the circuit of said trip coil operated in one direction with said operating member by said actuator, and in opposite direction in-

dependently of said actuator, and a control switch for said motive device movable with said trip coil switch.

27. The combination with an electric switch having a movable contact member, an operating member therefor, an actuator independent of said operating member, means for connecting said actuator and operating member for movement in one direction only, of a motive device for actuating said actuator in one direction only, means returning said actuator to normal position, a switch controlling said motive device, and means for moving said controlling switch in unison with said contact member independently of said motive device.

28. The combination with an electric switch having a movable contact member, an operating member therefor, an actuator independent of said operating member, means for connecting said actuator and operating member for movement in one direction only, of a motive device for actuating said actuator in one direction only, means returning said actuator to normal position, a switch controlling said motive device, means for moving said controlling switch in unison with said contact member independently of said motive device, a trip coil for disconnecting said actuator from said operating member, and a switch controlling said trip coil moving in unison with said contact member.

29. The combination with a circuit breaker and its tripping mechanism, of an operating member for said movable contact member, an actuator for said operating member movable independently thereof, a motive device for actuating said actuator in one direction only, and means preventing operation of said motive device until after said circuit breaker has been tripped.

30. The combination with a movable contact member of a switch or circuit breaker and its tripping mechanism, of an operating member for said contact member, an actuator for said operating member movable independently thereof, a motive device for actuating said actuator in one direction only, and means preventing operation of said tripping mechanism while said actuator is actuated by said motive device.

In testimony whereof I have hereunto affixed my signature in the presence of the two subscribing witnesses.

WILLIAM M. SCOTT.
